UNITED STATES PATENT OFFICE.

ADELBERT R. BENEDICT, OF SOUTH TACOMA, WASHINGTON.

PRESS.

Application filed August 16, 1924. Serial No. 732,542.

To all whom it may concern:

- Be it known that I, ADELBERT R. BENEDICT, a citizen of the United States, residing at South Tacoma, in the county of Pierce and State of Washington, have invented certain new and useful Improvements in Presses, of which the following is a specification, reference being had to the accompanying drawings.
- 10 This invention relates to presses and more particularly to a combination press and vise particularly adapted for use in removing broken handles from axes, hammers and the like and to hold the helves of these devices 15 while they are being fitted to the heads thereof.

An important object of the invention is the provision of a device of this character so constructed that a head having a fragment 20 of the handle remaining therein may be readily held and readily placed in position in the press.

A further object of the invention is to provide a means for separating the head 25 from the press die by means of which the fragment of the handle is removed in event the die sticks therein.

These and other objects I attain by the construction shown in the accompanying 30 drawings, wherein for the purpose of illustration is shown a preferred embodiment of my invention and wherein:—

Figure 1 is a side elevation of a press constructed in accordance with my invention, parts being broken away to show details of construction and an axe head being indicated in position in the press;

Figure 2 is a section on the line 2—2 of Figure 1;

40 Figure 3 is a section on the line 3—3 of Figure 1;

Figure 4 is a section on the line 4—4 of Figure 1;

Figure 5 is a transverse sectional view 45 through the press, the shiftable base section being removed;

Figure 6 is a bottom plan view of the base section removed;

Figures 7 and 8 are detail plan views of 50 different forms of dies;

Figure 9 is a fragmentary front elevation of the press showing the same in use as a pipe vise.

Referring now more particularly to the 55 drawings, the numeral 10 indicates a base

having extending upwardly therefrom a pair of spaced standards 11, these standards having their adjacent faces 12 smooth and the adjacent side faces 13 similarly finished. The standards at their upper ends are connected by a bridge-piece 14 through which is threaded a lever screw 15, the lower end of which has a head 16 connected with the screw by a reduced neck 17.

The numeral 18 designates a press bar 60 consisting of a casting having a width equal to the distance between adjacent faces 12 of the standards 11 and provided at one side thereof with flanges 19 abutting the side face 13 of the standard at one side thereof. 65 The upper surface of the press bar has formed therein a slot 20 opening through the opposite side of the bar from the flanges 19, this slot being of a width equal to the width of the head 16 and having extending outwardly from the side walls thereof flanges 21 adapted to engage in the groove 70 formed by the reduced neck 17 connecting the lever screw with its head. Since this slot opens through the side of the press bar, 75 it will be obvious that the press bar can be engaged with the lever screw and mount the same thereon with very little difficulty. Disengagement of the bar therefrom is prevented by a retainer strip 22 secured to the 80 side of the bar through which the groove opens and having its ends abutting the side faces of the standards 11 at the opposite side thereof from the flanges 19. The under surface of the press bar is provided with a 85 depending lug 23 which is centrally socketed for the reception of the shanks 24 of various implements 25 to be employed therewith. These implements will hereinafter be more fully described. After the shanks of the 90 implements are inserted, they are maintained in position by a pin passed through an opening in the shank of the implement and in the wall of the lug.

The base 10 has formed through one side 100 thereof an arcuate notch 27, the inner end of which terminates in a semi-circular cove 28, the axis of the curvature of the cove being concentric with the axis of the lever screw 15. Pivoted to the base at one side 105 of the notch is an arm 29, the pivot 30 of which permits vertical as well as rotative movement thereof. The inner face of this arm is adapted to abut against the adjacent faces 13 at the lower ends thereof to limit 110

the movement of the arm in this direction. At the opposite side of the notch, and spaced from the adjacent face 13 a distance equal to the width of the arm at this point, 5 an upstanding lug 31 is formed on the base. The arm may be engaged between this lug and the face 13 of the standard by elevating the same on the pivot and swinging the arm until the free end thereof comes into 10 engagement with the face 13 when the arm may be released and will fall by gravity to the proper position. The lower surface of the arm is provided with a thickening or flange 32 filling the slot when the arm is in 15 this position. The inner face of the arm is provided with a notch 33 coacting with the notch 28 to produce a circular opening in the base which is axial to the lever screw 15. Directed through the standards 11, at 20 points spaced slightly above the base, are a pair of thumb screws 34 which are employed for steadyng the work upon the base. Slightly above these set screws, the arm is provided with aligned apertures 35 for the 25 reception of stop bars 36, the purpose of which will presently appear.

In the use of the device, assuming it is desired to remove the handle from an ax, hammer or the like, the proper die is selected for this purpose. In Figures 7 and 30 8 I have illustrated dies suitable for use with an ax and a hammer respectively. The die being placed in position, the head of the hammer is then placed in position upon the 35 base. If the handle is cleanly broken off at the head, this may be accomplished by simply seating the head upon the base. If a fragment of the handle is left within the head, the swinging arm is moved to open 40 the slot, the handle entered through this slot and the arm closed so that the head rests thereon. It will be obvious that when pressure is placed upon this head it will be impossible for this arm to move from the 45 open position to permit dislodgment of the head. In either case, as soon as the head is in position it is secured against accidental sidewise displacement by tightening the thumb screws 34, after which the die is 50 brought downwardly by means of the lever screw to force the handle out of the head. In event the die sticks in the head after the handle has been forced from the head, the stop bars 36 are placed in position so 55 that they engage the head at the sides of the die and the lever screw operated to move the die and head upwardly. When it is desired to employ the device for holding pipe or a helve to be shaped and fitted to a 60 head, the V block 37, illustrated in Figure 9, is employed, together with the toothed anvil of this figure. The walls of this V

block are preferably step-cut to provide teeth for preventing rotation of an article held therein. The other anvil further assists in preventing this movement and movement of the anvil itself with relation to the press bar is prevented by bringing the thumb screws 34 into engagement with the sides thereof.

It will be obvious that the construction hereinbefore set forth is capable of a certain range of change and modification without materially departing from the spirit of my invention, and I accordingly do not 75 limit myself to such specific structure except as hereinafter claimed.

I claim:

1. In a press of the type described, a base having a notch opening through one side 80 thereof and terminating centrally of the base in a semicircular cove, a pair of standards arranged at opposite sides of the cove and extending upwardly from the base, a bridge-piece connecting the standards at 85 their upper ends, a press bar guided by the standards and having means for attaching dies thereto, means extending through the bridge-piece for vertically adjusting the press bar upon the standards, a swingable 90 arm pivotally connected to the base at one end and combining with said base to fill the notch thereof and to combine with the cove of the notch to provide at the center of the base beneath the press bar an opening, the 95 pivotal connection of said arm and base permitting vertical movement of the arm with relation to the base, said arm in its closed position abutting the standards at one side face, and means upon the base engaging the 100 opposite side face of the bar when in the closed position preventing movement of the bar until the same is shifted vertically from the base.

2. In a press for removing the helves of 105 hammers, axes and the like, a base for supporting the head of the tool having a central opening and a slot leading to said central opening through which the handle of the tool may be inserted to permit the head 110 to rest upon the base; a closure for said slot pivoted to the base at one side of the slot by a pivot permitting limited vertical movement thereof, a member upon the base co-acting with the closure when in closed position to prevent opening thereof until the closure has been vertically shifted a pre-determined distance and a press carried by the base and having means for supporting dies in axial relation to the opening of the 115 base.

In testimony whereof I hereunto affix my signature.

ADELBERT R. BENEDICT.
